UNITED STATES PATENT OFFICE.

VERNON W. RUSSELL AND JESSE T. KYLE, OF BREA, AND JULIAN A. CAMPBELL, OF LONG BEACH, CALIFORNIA.

OIL BURNER.

Application filed March 15, 1921. Serial No. 452,517.

To all whom it may concern:

Be it known that we, VERNON W. RUSSELL and JESSE T. KYLE, citizens of the United States, and residents of Brea, county of 5 Orange, and State of California, and JULIAN A. CAMPBELL, a citizen of the United States, residing at Long Beach, in the county of Los Angeles and State of California, have invented new and useful Improvements in 10 Oil Burners, of which the following is a specification.

It is the object of this invention to provide an oil burner having means for thoroughly mixing the fuel with steam or 15 the like, by causing a whirling motion of the fuel and of the steam as the latter is discharged to the fuel. The mixed fuel and steam is then passed through a burner head 20 having an air chamber surrounding the same so as to produce an air space for the mixture of air with the combined fuel and steam. The discharge port for the mixed fuel and steam is preferably a relatively narrow elongated port, and the discharge port from 25 the air chamber and through which the mixed fuel, steam and air escapes, is a similar narrow elongated port so as to obtain the desired pressure.

The invention will be readily understood 30 from the following description of the accompanying drawings, in which—

Figure 1 is a longitudinal section through a burner constructed in accordance with the invention.

Fig. 2 is a detail section on the line 2—2 of Fig. 1.

Figs. 3 and 4 are transverse sections on the lines 3—3 and 4—4 of Fig. 1.

The fuel chamber of the burner is shown 40 at 1 as of relatively large diameter at its rear end, as shown at 2, and tapering to a relatively small diameter at its forward end as shown at 3. An end plate 4 is retained against the open rear end of the burner chamber as by a closure plate 5 threaded onto the end of the burner chamber and provided with the shoulder 6 engaging a shoulder 7 upon plate 4 for retaining the latter in position. The closure plate 5 is 45 provided with an axial opening and is connected to a conduit 8 as by a suitable threaded connection. A second conduit 9 extends through conduit 8 and through an axial opening 10 in plate 4 so that the inner 50 conduit discharges into the fuel chamber.

beyond the plate 4. The conduit 9 may be held in position with relation to plate 4 by means of a nut 11.

A T-joint 12 is preferably arranged upon conduit 8 with conduit 9 extending rearwardly beyond the same as through a pipe 13 provided in the end of the T-joint. A pipe 14 is connected to the angularly disposed nipple of the T-joint, said pipe being provided with a suitable valve 15, and a valve 16 is arranged in the rearwardly extending portion of conduit 9. The conduit 9 is connected to a suitable fuel supply, while the pipe 14 is connected to a steam supply in order that steam may be discharged through conduit 8 into a space 17 between plate 4 and the closure cap 5.

A concave baffle plate 18 is arranged in fuel chamber 1 over the discharge end of conduit 9, said baffle plate being preferably held in position by screws 19 received through the same and into plate 4. The axial portion of the baffle plate is spaced somewhat beyond the end of conduit 9, and the radially extending arms 20 of the baffle plate curve toward plate 4 with the ends of said arms forming restricted discharge 80 passages 21 between the baffle plate and plate 4 adjacent the wall of chamber 1. The arms 20 are so arranged that the discharge 85 ports 21 extend in opposite directions and are adapted to discharge fuel from the same circumferentially of fuel chamber 1. By this arrangement it will be seen that the fuel as discharged to the fuel chamber is 90 provided with a whirling motion as it travels axially of the fuel chamber.

The plate 4 is provided with discharge ports 22 communicating with the space 17 and tapering to restricted discharge ends 23 95 opening into the fuel chamber 1 adjacent the discharge port 21 provided by baffle 18. The ports 22 are inclined, as clearly shown in Fig. 2, with the discharge ends 23 thereof extending circumferentially of plate 4 and 100 in the direction of discharge through the respective ports 21, so that the steam discharged through ports 22 will also be provided with a whirling motion within the fuel chamber. By this arrangement it will 105 be seen that the fuel and steam will be thoroughly mixed during their passage through the fuel chamber.

A burner head 25 is connected to discharge end 3 of the fuel chamber by coupling 26, 110

and said burner head tapers outwardly somewhat towards its discharge end 27. The discharge end of the burner head is arranged as a relatively narrow elongated port, as 5 clearly shown in Fig. 4. An air conduit 28 surrounds the burner head and the discharge end 3 of the fuel chamber in spaced relation therefrom and is preferably supported by a spider 30. The ends of conduit 28 are open 10 so as to form an annular air passageway 31 surrounding the burner head, and the respective ends of the air conduit flare outwardly with the front end extending beyond the discharge port 27 of the burner head and 15 forming a discharge port 32 for the mixed fuel, steam and air. This discharge port is also arranged as a relatively narrow elongated opening, as clearly shown in Fig. 4.

The device as thus described provides for 20 the efficient mixture of steam and fuel in the fuel chamber of a burner, by setting up a whirling motion of the mixed fuel and steam, and the restricted discharge ports provided for the burner head and for the air 25 conduit, form means whereby the mixed fuel and steam after mixture with air in order to form a combustible product, will be discharged at high velocity through the burner.

Various changes may be made without departing from the spirit of the invention as 30 claimed.

What is claimed is:

1. A burner comprising a fuel chamber, a fuel supply conduit, a separate supply conduit for another fluid, and a fixed baffle in 35 said chamber over said supply conduits, said baffle having a concave lower surface and being spaced beyond the ends of said conduits and arranged to cause whirling discharge of said fuel to said chamber.

2. A burner comprising a fuel chamber, a fuel supply conduit, a separate supply conduit for another fluid, a fixed baffle in said chamber over said supply conduits, said baffle 45 having a concave lower surface and being spaced beyond the ends of said conduits and arranged to cause whirling discharge of said fuel to said chamber, and means for mixing a fluid with said fuel as it is discharged to 50 said chamber.

3. A burner comprising a fuel chamber, a fuel supply conduit, a separate supply conduit for another fluid, a fluid supply conduit,

a fixed baffle in said chamber over said fuel supply conduits, said baffle having a concave 55 lower surface and being spaced beyond the ends of said conduits and arranged to cause whirling discharge of said fuel to said chamber, and a discharge for said fluid supply to said chamber at the discharge edge of said 60 baffle.

4. In a burner, a mixing chamber, a partition arranged in one end thereof, which partition is provided with an inclined steam jet, opening means for supplying steam to the 65 chamber behind said partition, a fixed baffle plate arranged in front of said partition and provided with a nozzle that is arranged to discharge circumferentially relative to the walls of the fuel chamber, the open end of 70 said nozzle terminating adjacent to the steam jet opening through the partition, and means for supplying liquid hydrocarbon to the chamber between said partition and said baffle.

5. In a burner, a mixing chamber, a partition arranged in one end thereof, which partition is provided with an inclined steam jet, opening means for supplying steam to the 75 chamber behind said partition, a fixed baffle plate arranged in front of said partition and provided with a nozzle that is arranged to discharge circumferentially relative to the walls of the fuel chamber, the open end of 80 said nozzle terminating adjacent to the steam jet opening through the partition, means for supplying liquid hydrocarbon to the chamber between said partition and said baffle, said fuel chamber being provided with a fuel outlet and an air tube surrounding 85 said fuel outlet.

6. A burner comprising a fuel chamber, a fuel supply conduit, a fluid supply conduit, a fixed concave baffle in said chamber over said 90 fuel supply conduit and arranged to cause 95 whirling discharge of said fuel to said chamber, and a discharge for said fluid supply to said chamber at the discharge edge of said baffle and arranged to cause whirling discharge of said fluid.

In testimony whereof we have signed our names to this specification.
